CLAIM

The ornamental design for a diagnostic analyzer, as shown and described.

DESCRIPTION

FIG. 1 is a front perspective view of a diagnostic analyzer showing our new design;

FIG. 2 is a top view thereof;

FIG. 3 is a front view thereof;

FIG. 4 is a right side view thereof;

FIG. 5 is a left side view thereof; and,

FIG. 6 is a rear view thereof.

The broken lines in FIGS. 1-6 are for the purpose of illustrating the environment and form no part of the claimed design.
